UNITED STATES PATENT OFFICE.

GEORGE W. FISHERING, OF ALLEGHENY, PENNSYLVANIA.

MACHINE FOR FORMING CONICAL WIRE SPRINGS.

SPECIFICATION forming part of Letters Patent No. 292,799, dated February 5, 1884.

Application filed October 10, 1883. (No model.)

To all whom it may concern:

Be it known that I, GEORGE W. FISHERING, a citizen of the United States, residing at Allegheny, in the county of Allegheny and State of Pennsylvania, have invented new and useful Improvements in Machines for Forming Conical Wire Springs, of which the following is a specification.

My invention relates to improvements in machines for forming or coiling conical spiral metallic springs in pairs, in which the two springs that form the pair are alike and side by side, and are formed by a single wire, which connects them at their bases; and the objects 15 of my improvements are, first, to afford facilities for coiling the wire from each end by the agency of a single person by first forming one spring of the pair on a conical grooved mandrel, then the other on a similar mandrel, each 20 mandrel being journaled at fixed distances apart, about equal to the distance required between the springs of each pair when completed; second, to provide means of rotating both mandrels from the same drive-shaft; third, to 25 provide a press-block for holding the wire of the spring first coiled in the grooves of the mandrel, and at the same time locking the mandrel, so as to prevent it from uncoiling while the other spring is being coiled on the 30 other mandrel; fourth, to provide means of receiving the ends of the wire in the mandrels, so as to form a loop or eye at the end of the wire, so that the end will be retained while the remainder of the wire is being 35 coiled, and also that the spring may be easily released when completed. I attain these objects by the mechanism illustrated in the accompanying drawings, in which—

Figure 1 is a top plan of the machine showing the position of shafts and pinions as it appears when coiling the first spring of the pair. Fig. 2 is a top plan of the machine showing the position of shafts and pinions as it appears when coiling the second spring of the 45 pair. Fig. 3 is a side elevation. Figs. 4 and 5 are respectively a plan and elevation of a completed spring.

Similar letters refer to similar parts throughout the several views.

The letter A represents a metallic frame, which, with its bearings *a* and caps *b*, consti-

tutes the support for the working parts, it being provided with suitable holes in the base, so that it can be secured and attached to a suitable bench or table.

B B' are conical mandrels, fixed each, respectively, with their base ends to the shafts C C', each mandrel having a spiral groove, *b'*, formed in its exterior, terminating at the small end with a shoulder, *d'*. The shafts C C' are 55 journaled in suitable bearings in the frame A, and provided each, respectively, with a pinion, D D', which gear with a spur-pinion, E, which is carried on a shaft, F. The shaft F is also journaled in suitable bearings in the frame A, 60 and rotated by means of a crank, A'. The shaft F is provided with two circumferential flanges or guards, *c c*, both of which may be fixed at either end of the shaft, but preferably at the end to which the crank is attached, 70 and the distance between them being about equal to twice the thickness of the spur-pinion E, so as to allow the pinion E to free itself entirely from the pinion D and remain in gear with the pinion D' as the shaft F is 75 caused to slide forward longitudinally.

G is a bar having one end pivoted at *d* directly under the shaft C, and projecting in the same direction, passing through and extending beyond the slot *e* in the frame A a 80 distance about one-third the length of the mandrel B.

f is an upright tooth secured to the bar G directly under the pinion D.

g is a block secured to the end of the bar G, 85 having its upper side concaved, so as to fit the surface of the mandrel B.

H is a rod attached to the bar G under the block *g*, the lower end of which may be secured to an ordinary foot-pedal, by means of which 90 the bar G may be raised, so as to press the press-block *g* firmly against the mandrel B, at the same time forcing the tooth *f* between the teeth of the pinion D, thus locking the shaft and preventing it from revolving, and 95 the press-block preventing the wire of the spring from uncoiling while the other spring is being formed on the mandrel B'.

a' a' are pins secured firmly in the apexes of the mandrels B B', around which the wire I is 100 bent, so as to form a loop or eye, *c'*.

In operation the wire I is cut to a proper

length, and one end inserted in the recess between the pin a' and shoulder d' of the mandrel B. The operator by means of the crank A' holds the shaft F so that the spur-pinion 5 E gears with the pinion D, as shown in Fig. 1. Then by inserting the end of the wire in the apex of the mandrel B, and holding the wire rigid by hand, and by rotating the mandrel B, the loop or eye c' is formed, and the end of the 10 wire is thus retained while the remainder of the spring is being formed in the groove b' of the mandrel B. After sufficient wire has been coiled to form one of the springs, the operator by bearing on the foot-pedal forces the press-block g against the mandrel B, thus holding the wire in the grooves to prevent it from uncoiling, and also forcing the tooth f between the teeth of the pinion D, so as to prevent the shaft C from revolving, as shown in Fig. 3. 15 Then by sliding the shaft F forward longitudinally by means of the crank, so that the spur-pinion E passes out of gear with the pinion D and remains in gear with the pinion D', as shown in Fig. 2, the remainder of the wire, excepting the central part, (indicated by the dotted lines,) is coiled on the mandrel D' in the same manner as on the mandrel D. By raising the foot from the pedal the press-block g and the tooth f drop by gravity, and the coils 20 may be easily removed from the mandrels, and will be as shown in Figs. 4 and 5.

I do not confine myself to the exact position of pinions as shown, as they may be fixed in such relation to each other that when the spur-pinion E is in gear with either one of the pinions D D' it will be out of gear with the other. Thus each mandrel would be rotated independently of the other. But when in this position, 25 after the first spring has been formed on the

mandrel B, and after the press-block has been applied, there is some difficulty in entering the spur-pinion in the pinion D'. Therefore the position as shown is preferred.

Having thus described my invention, what I claim, and desire to secure by Letters Patent, 45 is—

1. In a machine for forming conical wire springs, the combination, with the conical grooved mandrels B B' and shafts C C', having pinions, respectively, D D', of the shaft F, having 50 spur-pinion E and guards c c, and arranged to slide backward and forward longitudinally, whereby one or each of said mandrels may be rotated independently of the other to form both coils of a conical spiral 55 twin spring from one drive-shaft, substantially as described, and for the purpose specified.

2. In a machine for forming conical wire springs, the combination, with the conical grooved mandrels B B' and shafts C C', having 60 pinions, respectively, D D', and sliding shaft F, of the hinged bar G, having upright tooth f, secured thereto, adapted to enter between the teeth of the pinion D, substantially as described, and for the purpose specified. 65

3. In a machine for forming conical wire springs, the combination, with the conical grooved mandrels B B' and shafts C C', having pinions, respectively, D D', and sliding shaft F, of the bar G, having a press-block, g, 70 secured to the end, adapted to press the wire in the groove of the mandrel D, substantially as described, and for the purpose specified.

G. W. FISHERING.
